CLAIM

The ornamental design for a escutcheon for push-pull valve assembly, as shown and described.

DESCRIPTION

FIG. 1 is a front perspective view;

FIG. 2 is a front elevation view;

FIG. 3 is a rear elevation view;

FIG. 4 is a top plan view;

FIG. 5 is a left side elevation view;

FIG. 6 is a right side elevation view;

FIG. 7 is a bottom plan view;

FIG. 8 is a top plan view of an alternate embodiment for which the front and rear elevation views are the same as shown in FIGS. 2 and 3;

FIG. 9 is a left side elevation view of the alternate embodiment shown in FIG. 8;

FIG. 10 is a right side elevation view of the alternate embodiment shown in FIG. 8; and,

FIG. 11 is a bottom plan view of the alternate embodiment shown in FIG. 8.

The broken lines shown in FIGS. 1-5 and 8-9 illustrate portions of the article and form no part of the claimed design.

1 Claim, 4 Drawing Sheets
